(57) CLAIM

The ornamental design for a wine case, as shown and described.

DESCRIPTION

FIG. 1 is a front perspective view of a wine case showing an embodiment of my new design;

FIG. 2 is a bottom perspective view of the wine case shown in FIG. 1;

FIG. 3 is a top view of the wine case shown in FIG. 1;
FIG. 4 is a bottom view of the wine case shown in FIG. 1;
FIG. 5 is a right-side view of the wine case shown in FIG. 1;

FIG. 6 is a left-side view of the wine case shown in FIG. 1;
FIG. 7 is a front view of the wine case shown in FIG. 1; and,
FIG. 8 is a front perspective view of the wine case shown in FIG. 1 with the top flaps closed.

The broken lines form no part of the invention.

1 Claim, 7 Drawing Sheets
